PYRIDOXOLYL-HYDROCARBON AND SUBSTITUTED HYDROCARBON DISULFIDES

Gustav Schorre, Darmstadt-Eberstadt, Germany, assignor to E. Merck Aktiengesellschaft, Darmstadt, Germany
 No Drawing. Filed Nov. 9, 1964, Ser. No. 409,950
 Claims priority, application Germany, Nov. 9, 1963,
 M 58,865
 5 Claims. (Cl. 260—294.8)

This invention relates to sulfur-containing pyridine derivatives, in particular to pyridyl disulfides and their acid addition salts.

The principal object of this invention, therefore, is to provide novel pyridyl disulfides and their acid addition salts.

Another object is to provide processes for their production, including the discovery of novel intermediates therefor.

Still another aspect of this invention is to provide novel pharmaceutical compositions and therapeutic methods, based on the novel compounds of this invention.

Upon further study of the specification and claims, other objects and advantages of the present invention will become apparent.

To attain the objects of the invention, there are provided compounds of the Formula I, and their acid addition salts, as follows:

wherein:

R₁ and R₂ represent hydrogen or acyl; and

R₃ represents: alkyl which can, if desired, be substituted; alkenyl; alkynyl; aryl or aralkyl, either of which can, if desired, be substituted.

The new compounds are derived from vitamin B₆ and its acyl derivatives, respectively.

The acyl residues R₁ and R₂ set forth in Formula I are preferably of saturated or unsaturated aliphatic monocarboxylic acids of up to 18 carbon atoms, particularly preferred residues being derived from the following acids: acetic acid, propionic acid, butyric acid, valeric acid, caproic acid, enanthic acid, caprylic acid, pelargonic acid, capric acid, undecylic acid, lauric acid, myristic acid, palmitic acid, stearic acid, acrylic acid, crotonic acid, oleic acid, elaidic acid, undecylenic acid, linoleic acid, and linolenic acid.

For the preferred embodiments of this invention, R₃ is selected from the group consisting of (a) unsubstituted alkyl of not more than 20 carbon atoms; (b) alkyl of not more than 20 carbon atoms substituted by at least one member selected from the group consisting of halogen, hydroxyl, lower alkoxy, amino, mono-(lower alkyl)-amino, di-(lower alkyl)-amino, piperidino, morpholino, piperazino and piperazino substituted by lower alkyl, aralkoxy wherein the aryl portion is a hydrocarbon of 6 to 10 carbon atoms and the alkoxy portion is a lower alkoxy, acyloxy of a hydrocarbon monocarboxylic acid of not more than 9 carbon atoms, carbobenzoxy, carboxyl, esterified carboxyl of not more than 9 carbon atoms wherein the alcohol portion is a hydrocarbon alcohol of not more than 8 carbon atoms, unsubstituted —CONH₂, —CONH₂ substituted by lower alkyl, piperidine, piperazine, and morpholide; (c) alkenyl of not more than 12 carbon atoms; (d) alkynyl of not more than 3 carbon atoms; (e) unsubstituted hydrocarbon aryl of not

2

more than 2 rings with 5 to 6 carbon atoms per ring; (f) unsubstituted aralkyl of the latter unsubstituted hydrocarbon aryl and a lower alkyl; and (g) a member selected from the group consisting of hydrocarbon aryl of not

5 more than 2 rings and 5 to 6 carbon atoms per ring and ar-lower alkyl of said hydrocarbon aryl, the aryl and ar-lower alkyl substituted by at least one member of the group consisting of halogen, lower alkyl, lower alkoxy, hydroxyl, nitro, amino, and lower mono- and di-alkyl-amino.

10 More particularly, R₃ can represent a straight-chain or branched, substituted or unsubstituted alkyl residue having generally no more than 20 carbon atoms. Suitable alkyl residues are particularly the lower alkyls, such as 15 methyl, ethyl, n-propyl, isopropyl, n-butyl, isobutyl, amyl, and isoamyl, and further those having a longer chain, such as hexyl, heptyl, octyl, nonyl, cetyl, undecyl, dodecyl, or lauryl.

The alkyl group can be mono- or poly-substituted.

20 Preferably, only such alkyl groups are substituted which do not contain more than 6 carbon atoms in the alkyl chain. Preferred substituents are halogens, such as, for example, fluorine, chlorine, or bromine; hydroxyl; lower alkoxy groups of up to about 5 carbon atoms, particularly

25 methoxy, ethoxy, n-propoxy, isopropoxy, n-butoxy, and isobutoxy. Also preferred is the amino group wherein one or both hydrogen atoms can likewise be substituted by lower alkyl groups (the alkyl groups being the same or different) having up to about 5 carbon atoms; these latter alkyl groups, in turn, can also be joined with one another, if desired, via a further hetero-atom, particularly a nitrogen or an oxygen atom. Of special importance are the 2-aminoethyl-, 3-amino-propyl-, 3-amino-2'-methyl-propyl-, and 4-aminobutyl-residues, as well as the

30 corresponding N-methyl-, N-ethyl-, N-propyl-, N-butyl-, N,N-dimethyl-, N,N-diethyl-, N-methyl-N-ethyl-, N,N-di-propyl-, N,N-di-tert.butyl-, and piperidino-derivatives.

35 Further substituents for the substituted alkyls are, for example, aralkoxy groups wherein the aryl is preferably

40 a hydrocarbon of 6 to 10 carbon atoms and the alkoxy is a lower alkoxy, particularly the benzyloxy residue, as well as acyloxy groups of aliphatic or aromatic carboxylic acids of up to 9 carbon atoms, preferably monocarboxylic acids, especially acetoxy, n-propanoxy, isopropanoiloxy, n-butanoyloxy, isobutanoyloxy, tert. butanoyloxy, and pentanoyloxy, and also benzoyloxy, toluyloxy, carbobenzoxy, or cinnamoyloxy. The alkyl residue R₃ can also be substituted by a free or by an esterified carboxyl group of up to 9 carbon atoms, i.e., for example by carboxyl, methoxycarbonyl, ethoxycarbonyl, propoxycarbonyl, butoxycarbonyl, also benzoyloxycarbonyl, and toloxycarbonyl. The alkyl group can also be substituted by

45 acid amide residues, —CONH₂; the hydrogen atoms of the amino group can also be replaced, in this connection, by lower alkyl residues which can also be connected with one another, if desired via another hetero-atom. Particularly suitable are, in addition to —CONH₂, the amides of methyl, ethyl, n-propyl, isopropyl, n-butyl, isobutyl, tert. butyl, dimethyl, diethyl, di-n-propyl, di-isopropyl, di-n-butyl, methylethyl, methyl-n-butyl, and ethyl-n-butyl, as well as the piperidides and morpholides.

50 The substituent R₃ of Formula I can also represent an alkenyl residue of generally not more than about 12 carbon atoms. This alkenyl residue can contain one or several double bonds, but generally no more than two. Preferred alkenyl residues are, for example, vinyl, allyl, butenyl, heptenyl, undecylene and butadienyl, hexadienyl, and heptadienyl. Alkynyl residues (R₃ in Formula I) 55 usually contain not more than 3 carbon atoms, and are preferably ethynyl and propargyl.

60 Additionally, R₃ can represent an aryl residue of not

65 70 75 80 85 90 95

more than 2 rings with 5 to 6 carbon atoms per ring. Hydrocarbon aryl, such as phenyl or naphthyl, is considered preferable. For aralkyl residues the same aryl nuclei can be employed. Particularly suitable are the benzyl and the phenethyl residues. If the aromatic nucleus, particularly the phenyl residue, is mono- or poly- (e.g. bi-) substituted, the substituents are preferably halogens, such as fluorine, chlorine, or bromine; or lower alkyl or alkoxy groups of up to 5 carbon atoms, especially methyl, ethyl, n-propyl, isopropyl, n-butyl, isobutyl, tert. butyl and amyl, and the corresponding alkoxy groups; or hydroxyl, nitro, amino, mono- and dialkylamino, preferably lower alkylamino groups, respectively. The following substituted aryl residues are set forth as preferred examples: o-, m-, or p-chlorophenyl; o-, m-, or p-bromophenyl; tolyl; xylyl; p-methoxyphenyl; o-, m-, or p-ethoxyphenyl; propoxyphenyl; hydroxyphenyl; nitrophenyl; aminophenyl; aminotolyl; 2-amino-3-hydroxyphenyl; 2-methoxy-3-aminophenyl; N-methyl-aminophenyl; N-ethyl-aminophenyl; N-methyl-N-butyl-aminophenyl; N,N-di-tert. butyl-aminophenyl; 2-methyl-4-chlorophenyl; and 2,4-dimethyl-phenyl.

The following structural compounds, as well as their acid addition salts, particularly the hydrochlorides, represent preferred embodiments of this invention:

wherein $n=1$ or 2.

R_1 and R_2 have the previously indicated significance.

Of the compounds included in the above formulae, the following are particularly preferred, the pyridoxyl radi-

75

cal being represented by Formula I when R_1 and R_2 are both hydrogen:

- 5 Pyridoxyl-methyl-disulfide
 Pyridoxyl-ethyl-disulfide
 Pyridoxyl-propyl-disulfide
 Pyridoxyl-butyl-disulfide
 Pyridoxyl-amyl-disulfide
 Pyridoxyl-cetyl-disulfide
 10 Pyridoxyl-lauryl-disulfide
 Pyridoxyl-vinyl-disulfide
 Pyridoxyl-allyl-disulfide
 Pyridoxyl-crotyl-disulfide
 Pyridoxyl-undecylenyl-disulfide
 15 Pyridoxyl-ethynyl-disulfide
 Pyridoxyl-propargyl-disulfide
 Pyridoxyl-phenyl-disulfide
 Pyridoxyl-naphthyl-disulfide
 Pyridoxyl-benzyl-disulfide
 20 Pyridoxyl-phenethyl-disulfide
 Pyridoxyl-4'-methoxybutyl-disulfide
 Pyridoxyl-4'-ethoxybutyl-disulfide
 Pyridoxyl-4'-butoxybutyl-disulfide
 Pyridoxyl-4'-benzyloxybutyl-disulfide
 25 Pyridoxyl-4'-acetoxybutyl-disulfide
 Pyridoxyl-4'-propoxybutyl-disulfide
 Pyridoxyl-3'-benzoyloxypropyl-disulfide
 Pyridoxyl-4'-cinnamoyloxybutyl-disulfide
 Pyridoxyl-3'-carboxypropyl-disulfide
 30 Pyridoxyl-1'- β -ethoxycarbonylethyl-disulfide
 Pyridoxyl- β -methoxycarbonylethyl-disulfide
 Pyridoxyl-3'-toloxycarbonylpropyl-disulfide
 Pyridoxyl-2'-ethoxyheptylpropyl-disulfide
 Pyridoxyl-2'-carbamoylethyl-disulfide
 35 Pyridoxyl-4'-N,N-dimethylcarbamoylbutyl-disulfide
 Pyridoxyl-3'-N,N-di-tert.butyl-carbamoylpropyl-disulfide
 Pyridoxyl-2'-N-methyl-N-ethylcarbamoylethyl-disulfide
 Pyridoxyl-2'-morpholido-ethyl-disulfide
 40 Pyridoxyl-3'-piperididopropyl-disulfide
 Pyridoxyl-2'-hydroxyethyl-disulfide
 Pyridoxyl-2'-aminoethyl-disulfide
 Pyridoxyl-3'-diethylaminopropyl-disulfide
 Pyridoxyl-(3'-N,N-diethylamino-2'-methylpropyl)-disulfide
 45 Pyridoxyl-3'-piperidinopropyl-disulfide
 Pyridoxyl-chlorophenyl-disulfide
 Pyridoxyl-p-methoxyphenyl-disulfide
 Pyridoxyl-o-tolyl-disulfide
 Pyridoxyl-p-hydroxyphenyl-disulfide
 50 Pyridoxyl-o-nitrophenyl-disulfide
 Pyridoxyl-o-aminophenyl-disulfide
 Pyridoxyl-2-amino-3-hydroxyphenyl-disulfide
 Pyridoxyl-2-methoxy-3-aminophenyl-disulfide
 Pyridoxyl-2-methyl-4-chlorophenyl-disulfide
 55 Pyridoxyl-3,5-dimethylphenyl-disulfide
 Pyridoxyl-2,3-dimethylphenyl-disulfide
 Pyridoxyl-2-chloro-4-methylphenyl-disulfide
 Pyridoxyl-2-chlore-4,5-dimethylphenyl-disulfide
 Pyridoxyl-3,4-dimethoxyphenyl-disulfide
 60 Pyridoxyl-2-methyl-3,6-dichlorophenyl-disulfide
 Pyridoxyl-2-trifluoromethyl-4-methylphenyl-disulfide
 Pyridoxyl-2-methyl-4-diethylaminophenyl-disulfide
 Pyridoxyl-3-methyl-5-hydroxyphenyl-disulfide
 Pyridoxyl-2'-piperazinylethyl-disulfide
 65 Pyridoxyl-p-xylyl-disulfide

When R_1 and/or R_2 represent acyl, the particularly preferred compounds are 3-acetoxy-4-acetoxymethyl-, 3-butoxy-4-butoxymethyl-, 3-heptoxy-4-heptoxyethyl-, 3-octoxy-4-octoxymethyl-, 3-undecylenoxy-4-undecylenoxy-methyl-, and 3-stearyloxy-4-stearyloxyethyl-compounds. These compounds are thus derivatives of the compounds generically and specifically described on Col. 4, lines 4 through 66.

Further specific embodiments are:

- [2-methyl-3-acetoxy-4-acetoxymethyl-pyridyl-(5)-methyl]-n-butyl-disulfide
- [2-methyl-3-acetoxy-4-acetoxymethyl-pyridyl-(5)-methyl]-ethyl-disulfide
- [2-methyl-3-acetoxy-4-acetoxymethyl-pyridyl-(5)-methyl]-allyl-disulfide
- [2-methyl-3-acetoxy-4-acetoxymethyl-pyridyl-(5)-methyl]-2-methyl-3,6-dichlorophenyl-disulfide
- [2-methyl-3-propionyloxy-4-propionyloxymethyl-pyridyl-(5)-methyl]-ethyl-disulfide
- [2-methyl-3-propionyloxy-4-propionyloxymethyl-pyridyl-(5)-methyl]-benzyl-disulfide
- [2-methyl-3-propionyloxy-4-propionyloxymethyl-pyridyl-(5)-methyl]-isopropyl-disulfide
- [2-methyl-3-propionyloxy-4-propionyloxymethyl-pyridyl-(5)-methyl]-2,3-dimethylphenyl-disulfide
- [2-methyl-3-palmitoyloxy-4-palmitoyloxymethyl-pyridyl-(5)-methyl]-ethyl-sulfide
- [2-methyl-3-palmitoyloxy-4-palmitoyloxymethyl-pyridyl-(5)-methyl]-ethyl-sulfide
- [2-methyl-3-palmitoyloxy-4-palmitoyloxymethyl-pyridyl-(5)-methyl]-benzyl-sulfide
- [2-methyl-3-palmitoyloxy-4-palmitoyloxymethyl-pyridyl-(5)-methyl]-p-xyl-sulfide
- [2-methyl-3-palmitoyloxy-4-palmitoyloxymethyl-pyridyl-(5)-methyl]-cetyl-sulfide
- [2-methyl-3-undecylenyloxy-4-undecylenyloxymethyl-pyridyl-(5)-methyl]-isobutyl-disulfide

The novel compounds can be produced as follows:

(a) By reacting a pyridine derivative of Formula II:

wherein:

R₁ and R₂ have the previously indicated meanings, and R₄ represents hydrogen, ammonium, or an equivalent of a metallic atom, preferably an alkali metal such as sodium,

or its acid addition salt, with a sulfur-containing compound of Formula III:

wherein:

Y represents $-SO_3R_4$, $-SO_2R_3$, $-SOR_3$, Br, Cl, or $-S-CN$, and

R₃ and R₄ have the previously indicated meanings.

(b) Or by reacting a sulfur-containing pyridine derivative of Formula IV:

wherein:

Z represents $-SO_3R_4$, Cl, or Br, and R₁, R₂, and R₄ have the previously indicated meanings,

or its acid addition salt, with a mercaptan derivative of Formula V:

wherein: R₃ and R₄ have the previously indicated meanings.

If desired, a compound of Formula I wherein R₁ and/or R₂ represent hydrogen can be treated with an acylating agent; or a compound of Formula I wherein R₁ and/or

R₂ represent acyl can be treated with a saponification agent. Further, a compound of Formula I can be converted, in a conventional manner, to its acid addition salt; or similarly the base compound can be liberated from an acid addition salt if the latter is obtained as a reaction product.

The details of the various processes for producing the compounds of this invention are as follows:

Reaction (a).—The reaction of a 3-mercaptomethyl-pyridine compound of Formula II with the derivatives of thiosulfuric acid (Y=SO₃R₄), preferably with Bunte's salts (salts of alkylthiosulfuric acids) is advantageously conducted in alkaline solution and in water, or in solvents which are miscible with water, for example in lower aliphatic alcohols, acetone, dimethyl formamide, dioxane, or tetrahydrofuran. It is, of course, also possible to use mixtures of such solvents, particularly mixtures of water and alcohols. Suitable alkaline materials are, for example, sodium hydroxide, potassium hydroxide, or ammonium hydroxide. Normally, the reactions are carried out at temperatures between 0 and 80° C. and under normal pressure.

The reaction between a 3-mercaptomethyl-pyridine compound of Formula II and such sulfur-containing compounds of Formula III wherein Y represents SO₂R₃ or SOR₃ is suitably carried out in approximately neutral solution. The yields of the desired end products generally decrease substantially in strongly acidic or strongly alkaline solution. Especially suitable for conducting the reaction are polar solvents, particularly alcohols, such as methanol, ethanol, propanol, and isopropanol. The reaction can be conducted in the absolute alcohols, as well as in aqueous alcoholic solution. The reaction temperatures are generally between 0 and about 100° C.; preferably, however, room temperature is employed. Normally, it is sufficient to allow the reaction mixture to stand for a few hours.

Also, the reaction of the 3-mercaptomethyl-pyridine derivatives of Formula II with substituted sulfenyl halogenides (Y=Cl or Br) or substituted sulfenyl thiocyanates (Y=—S—CN) of Formula III is conducted in a solvent; preferably, inert solvents, such as ether, isopropylether, dioxane, dimethyl formamide, methylene chloride, chloroform, carbon tetrachloride, carbon disulfide, or ethyl acetate are added. Normally, the reaction mixture is allowed to stand at room temperature for several hours. However, it is also possible to carry out the reaction at higher temperatures.

The sulfenyl thiocyanates (Formula III, Y=—S—CN) necessary for the reaction, which are produced generally by reaction of metallic salts of thiocyanic acid with the correspondingly substituted mercaptan derivatives, do not have to be employed in the reaction in the form of pure products, but they can also be utilized in situ.

Reaction (b).—For reacting a sulfur-containing pyridine derivative of Formula IV wherein Z represents halogen with the mercaptan derivatives of Formula V, inert solvents are likewise used, such as ether, dioxane, dimethyl formamide, chlorinated hydrocarbons, carbon disulfide or ethyl acetate. Here, too, it is recommended that the reaction mixture be allowed to stand for a longer period of time, for example overnight, at room temperature; however, it is also possible to heat the reaction mixture to increase the rate of reaction.

In contradistinction thereto, if a sulfur-containing pyridine derivative of Formula IV, wherein Z represents SO₃R₄, is reacted with a mercaptan derivative of Formula V, it is advantageous to conduct the reaction in water and/or in solvents miscible with water, such as, for example, in lower aliphatic alcohols, acetone, dimethyl formamide, dioxane, or tetrahydrofuran. The pH value of the reaction mixture is advantageously held above 7, preferably between 7 and 11. Generally, aqueous solutions of sodium, potassium, or ammonium hydroxide are added in order to obtain these pH values.

According to this invention, it is possible, in connection with compounds of Formula I wherein R_1 and/or R_2 represent hydrogen, to substitute these H atoms by acyl groups. For this reaction, any conventional acylating method can be utilized. Particularly advantageous is the reaction with the corresponding acid anhydrides and/or acid chlorides of the above-mentioned acids in the presence of alkaline agents, particularly pyridine. For introducing the acyl residues of longer-chain acids, the acid chlorides are preferably employed.

It is also possible to transform such compounds of Formula I wherein R_1 and/or R_2 represent an acyl residue into the corresponding 3-hydroxy-4-hydroxymethyl compounds by treatment with saponification agents. Such a saponification can be conducted in accordance with any conventional process, for example by the effect of dilute acids or bases. The saponification process is especially smooth if the mixture is allowed to stand for a long period of time at room temperature with dilute acids, such as, for example, hydrochloric acid. However, the saponification can also take place through the effect of aqueous or aqueous-alcoholic solutions of, for example, sodium carbonate or bicarbonate.

The isolation of the reaction products is also done in a conventional manner, for example, by precipitating with the addition of a miscible non-solvent; by evaporating the solvent; by extraction; or by chromatographic methods.

The conversion of the compounds of Formula I into their acid addition salts is likewise conventional, for example, by reaction with the corresponding acid in an inert solvent. For pharmaceutical uses, all acids can be employed which yield physiologically compatible acid addition salts. Preferably, the following acids are contemplated: hydrochloric acid, hydrobromic acid, phosphoric acid, sulfuric acid, nitric acid, methanesulfonic acid, and alkylsulfonic acids, such as p-toluenesulfonic acid. In those cases in which the compounds according to the processes of the invention are obtained by acid addition salts, for example as hydrochlorides, they can obviously be converted into the corresponding free bases by any well-known technique, for example by neutralizing the solution of the acid addition salt and subsequently isolating the liberated base.

The starting compounds of Formula II are known from U.S. Patent No. 3,010,966 (e.g. claim 2) or they can be produced therefrom by conventional reaction with an acylating agent (R_1 and/or R_2 representing acyl) or with an alkali metal or ammonium hydroxide (R_4 representing an alkali metal or ammonium equivalent). Compounds of Formula IV wherein Z represents SO_3R_4 are obtained by reacting the corresponding 3-bromomethyl-pyridine compound with the desired thiosulfate.

The compounds of Formula III wherein $Y=SO_3R_4$ which are used as starting materials, are obtained, in a known manner, by reacting the corresponding halogenides (preferably the bromides such as R_3Br) with sodium thiosulfate.

The thiosulfonic acid derivatives of Formula III ($Y=SOR_3$) can be produced, in a known manner, by oxidation of the corresponding disulfides ($R_3-S-S-R_3$) with perbenzoic acid.

The thiosulfonic acid derivatives of Formula III ($Y=SO_2R_3$) are formed by heating the correspondingly substituted sulfenic acids (R_3SO_2H) in water, the thiosulfonates being precipitated by disproportionation according to the following reaction:

The sulfenyl thiocyanates of Formula III ($Y=SCN$) which are further compounds usable as starting materials can be obtained, as mentioned above, by reacting rhodanates with the correspondingly substituted mercaptan derivatives.

The novel compounds of Formula I and their acid addition salts can be employed as therapeutic drugs and can be particularly utilized in cases wherein vitamin B₆ therapy is indicated, more particularly for the treatment of cerebral malfunctions. In comparison to the known symmetrical pyridoxolyl disulfide, the novel compounds exhibit a higher lipoid solubility. For this reason, they penetrate the cellular membranes more readily and thus are better absorbed by the lipoid-rich nerve tissue.

These compounds can be employed in a mixture with the conventional pharmaceutical excipients. Carrier substances can be such organic or inorganic substances which are suitable for parenteral or enteral application and which do not react with the novel compounds, such as, for example, water, vegetable oils, polyethylene glycols, gelatine, lactose, amylose, magnesium stearate, talcum, Vaseline, cholesterol, etc. For parenteral application, solutions are especially used, preferably oily or aqueous solutions, as well as suspensions or emulsions which, if desired, are used in sterilized form or mixed with auxiliary agents, such as preservatives, stabilizers, or wetting agents, or with salts for influencing the osmotic pressure, or with buffer substances. For enteral application, tablets or dragees are particularly suitable.

It is, of course, also possible to combine the novel compounds with other drugs, the concentration being, of course, compatible. Of special importance are polyvitamin combinations.

With respect to dosage, obviously effective amounts are administered. A unit dosage of a compound of this invention comprises on the order of 10 to 500 mg. preferably 50 to 100 mg.

Without further elaboration, it is believed that one skilled in the art can, using the preceding description, utilize the present invention to its fullest extent. The following preferred specific embodiments are, therefore, to be construed as merely illustrative, and not limitative of the remainder of the specification and claims in any way whatsoever.

Example 1

(a) 2.75 g. 2-methyl-3-hydroxy-4-hydroxymethyl-5-mercaptopethyl-pyridine are dissolved in a mixture of 15 ml. water and 25 ml. of 1 N-sodium hydroxide, and mixed with 3.5 g. butylthiosulfate (Bunte's salt). The reaction mixture is allowed to stand for 10 minutes at room temperature, and the obtained precipitate is removed by suction. After recrystallization from benzene, the obtained [2-methyl-3-hydroxy-4-hydroxymethyl - pyridyl - (5)-methyl]-n-butyl-disulfide melts at 100° C. Yield: 2.2 g.

(b) 2 g. [2 - methyl - 3-hydroxy-4-hydroxymethyl-pyridyl-(5)-methyl]-n-butyl-disulfide are allowed to stand overnight at 0° C. with 10 ml. pyridine and 10 ml. acetic anhydride. Thereafter, the reaction mixture is mixed with water. The oil which separates during this process is taken up in ethyl acetate. After the solution is dried over sodium sulfate, the solvent is evaporated. The residue of [2-methyl-3-acetoxy-4-acetoxyethyl-pyridyl-(5)-methyl]-n-butyl-disulfide melts, after recrystallization, at 37-38° C.

Example 2

(a) 120 g. 2-methyl-3-hydroxy-4-hydroxymethyl-pyridyl-(3)-methyl-bromide are slowly added to 800 ml. acetyl chloride in an ice bath and under vigorous stirring; subsequently, the mixture is refluxed for 2 hours. The precipitated 2-methyl-3-acetoxy-4-acetoxyethyl-pyridyl - (3)-methyl-bromide-hydrochloride is removed by suction, and subsequently dissolved in water; the aqueous solution is adjusted to a pH of 7 by means of dilute sodium hydroxide. The 2-methyl-3-acetoxy-4-acetoxyethyl-pyridyl-(5)-methylbromide which precipi-

tates is removed by suction and recrystallized from isopropyl ether. M.P. 90° C. Yield: 107 g.

9.15 g. of the compound thus obtained are suspended in 50 ml. alcohol and mixed, under stirring, with a solution of 7.2 g. sodium thiosulfate in 10 ml. water. The mixture is heated for 1 1/4 hours to 60° C., is then filtered, and mixed with 20 ml. ether. The 2-methyl-3-acetoxy-4-acetoxy-methyl-pyridyl-(5)-methyl-thiosulfate-sodium which precipitates is removed by suction and recrystallized from methanol/ether. M.P. 238° C. (decomposition). Yield: 9 g.

3.17 g. of the thus-obtained thiosulfate are added to a solution of 0.9 g. n-butyl-mercaptan in 25 ml. 0.5 N NaOH. The reaction mixture is allowed to stand for 5 minutes at room temperature, and the oil which is separated is taken up in ethyl acetate. The reaction mixture is dried over sodium sulfate and concentrated by evaporation. The oily residue of [2-methyl-3-acetoxy-4-acetoxy-methyl-pyridyl-(5)-methyl]-n-butyl-disulfide crystallizes by trituration with hexane. M.P. 37-38° C. (hexane). Yield: 2.3 g.

(b) 0.3 g. [2-methyl-3-acetoxy-4-acetoxy-methyl-pyridyl-(5)-methyl]-n-butyl-disulfide is allowed to stand in 5 cc. 1 N-hydrochloric acid for 24 hours at room temperature. The solution is neutralized in 2 N-solution of sodium bicarbonate. After the mixture is worked up in conventional manner, 0.17 g. pyridoxolyl-n-butyl-disulfide is obtained, M.P. 100° C.

Example 3

2.75 g. 2-methyl-3-hydroxy-4-hydroxymethyl-5-mercaptopethyl-pyridine are dissolved in 40 ml. 0.5 N NaOH and mixed with 4.5 g. lauryl thiosulfate. The reaction mixture is heated for 15 minutes to 50-55° C. The precipitated [2-methyl-3-hydroxy-4-hydroxymethyl-pyridyl-(5)-methyl]-lauryl-disulfide is removed by suction and recrystallized from benzene. M.P. 114-115° C. Yield: 2.8 g.

Example 4

8.7 g. 1-propanethiosulfonic acid propyl ester are dissolved in 150 ml. methanol and mixed with a solution of 22.1 g. 2-methyl-3-hydroxy-4-hydroxymethyl-5-mercaptopethyl-pyridine-hydrochloride in 100 ml. methanol. After the mixture has been allowed to stand at room temperature for 6 hours, 50 ml. ether are added. The [2-methyl-3-hydroxy-4-hydroxymethyl-pyridyl-(5)-methyl]-n-propyl-disulfide-hydrochloride which precipitates is removed by suction and recrystallized from isopropyl alcohol/ether. M.P. 117-118° C. Yield: 19 g.

If the ethereal solution is adjusted to a pH of approximately 7 by the addition of NaOH, the free base can be isolated. M.P. 114° C. (benzene).

Example 5

11.9 g. isopentanethiosulfonic acid isoamyl ester are dissolved in 30 ml. absolute alcohol and mixed with a solution of 9 g. 2-methyl-3-hydroxy-4-hydroxymethyl-5-mercaptopethyl-pyridine in 50 ml. absolute alcohol. After the mixture has been allowed to stand for 12 hours at room temperature, it is evaporated to dryness under vacuum. The residue is mixed with 2 N-aqueous solution of sodium bicarbonate. The [2-methyl-3-hydroxy-4-hydroxymethyl-pyridyl-(5)-methyl]-isoamyl-disulfide which separates is removed by suction and recrystallized from benzene. M.P. 114-115° C. Yield: 7.4 g.

Example 6

22.5 g. lead rhodanate are suspended in 150 ml. absolute ether and mixed with 3 ml. bromine at 5-10° C. Once the mixture loses its color, the precipitated lead bromide is removed by suction. A solution of 5.5 g. thiophenol in 100 ml. dimethyl formamide is slowly added, dropwise, to the filtrate at 10° C. The reaction is subsequently mixed with a solution of 9.2 g. 2-methyl-3-hydroxy-4-hydroxymethyl-5-mercaptopethyl-pyridine in

100 ml. dimethyl formamide. After the mixture has been allowed to stand overnight, 2.5 l. ether are added. The separated oil is dissolved in 50 ml. 2 N-hydrochloric acid. The portion which does not dissolve (diphenyl disulfide) is removed by suction. The filtrate is evaporated to dryness, and the residue is taken up in water, neutralized, and extracted with ethyl acetate. The ethyl acetate solution is freed from precipitating by-products and dried over sodium sulfate. After concentration and recrystallization from ethyl acetate, the [2-methyl-3-hydroxy-4-hydroxymethyl-pyridyl-(5)-methyl]-phenyl-disulfide melts at 108° C. Yield: 4 g.

Example 7

15 9.2 g. 2-methyl-3-hydroxy-4-hydroxymethyl-5-mercaptopethyl-pyridine are dissolved in 100 ml. dimethyl formamide. The solution is mixed with 4.8 g. o-nitrobenzene sulfenylchloride in 50 ml. dimethyl formamide. The reaction mixture is stirred for 2 hours at room temperature and is then allowed to stand overnight. The obtained precipitate is removed by suction, and the filtrate is concentrated to about 1/3 its volume and mixed with 500 ml. water. The precipitating substance is removed by suction, washed with 20 ml. 1 N-hydrochloric acid, and recrystallized from methanol/ether. The obtained [2-methyl-3-hydroxy-4-hydroxymethyl-pyridyl-(5)-methyl]-o-nitrophenyl-disulfide melts at 163° C. Yield: 1.3 g.

Example 8

30 Analogously to Example 1, the following compounds are obtained by reaction of 2-methyl-3-hydroxy-4-hydroxymethyl-5-mercaptopethyl-pyridine with the corresponding alkylthiosulfates:

35 (a) [2-methyl-3-hydroxy-4-hydroxymethyl-pyridyl-(5)-methyl]-ethyl-disulfide: M.P. 128° C. (benzene); hydrochloride: M.P. 121-122° C. (isopropanol/ether).

(b) [2-methyl-3-hydroxy-4-hydroxymethyl-pyridyl-(5)-methyl]-propyl-disulfide: M.P. 114-115° C. (benzene); hydrochloride: M.P. 117-118° C. (isopropanol/ether).

(c) [2-methyl-3-hydroxy-4-hydroxymethyl-pyridyl-(5)-methyl]-isopropyl-disulfide: M.P. 145° C. (benzene); hydrochloride: M.P. 117-118° C. (isopropanol/ether).

(d) [2-methyl-3-hydroxy-4-hydroxymethyl-pyridyl-(5)-methyl]-isobutyl-disulfide: M.P. 100° C. (benzene); hydrochloride: M.P. 97° C. (isopropanol/ether).

(e) [2-methyl-3-hydroxy-4-hydroxymethyl-pyridyl-(5)-methyl]-allyl-disulfide: M.P. 118° C. (benzene).

(f) [2-methyl-3-hydroxy-4-hydroxymethyl-pyridyl-(5)-methyl]-cetyl-disulfide: M.P. 110° C.

Example 9

55 Analogously to the method described in Example 1, 2.75 g. 2-methyl-3-hydroxy-4-hydroxymethyl-5-mercaptopethyl-pyridine are reacted with benzylthiosulfate to form [2-methyl-3-hydroxy-4-hydroxymethyl-pyridyl-(5)-methyl]-benzyl-disulfide. M.P. 140° C. (methanol).

Example 10

Analogously to the method set forth in Example 1, 2.75 g. 2-methyl-3-hydroxy-4-hydroxymethyl-5-mercaptopethyl-pyridine are reacted with phenylthiosulfate to form [2-methyl-3-hydroxy-4-hydroxymethyl-pyridyl-(5)-methyl]-phenyl-disulfide. M.P. 108° C. (ethyl acetate).

Example 11

70 Analogously to the method described in Example 1, 2.75 g. 2-methyl-3-hydroxy-4-hydroxymethyl-5-mercaptopethyl-pyridine are reacted with 4'-acetoxy-butylthiosulfate to yield [2-methyl-3-hydroxy-4-hydroxymethyl-pyridyl-(5)-methyl]-4'-acetoxybutyl-disulfide. M.P. 71-72° C. (benzene/isopropyl ether).

11

Example 12

Analogously to the method mentioned in Example 1, 2.75 g. 2-methyl-3-hydroxy-4-hydroxymethyl-5-mercaptop-methylpyridine are reacted with β -ethoxy-carbonylethyl-thiosulfate to yield [2 - methyl - 3 - hydroxy-4-hydroxymethyl - pyridyl - (5) - methyl] - β - ethoxy-carbonylethyl-disulfide. M.P. 71° C. (isopropyl ether/hexane).

Example 13

Analogously to the method described in Example 1, 5.4 g. 2-methyl-3-hydroxy - 4 - hydroxymethyl-5-mercaptop-methylpyridine are reacted with 11.6 g. p-chlorophenoxy-ethylthiosulfate to form [2-methyl-3-hydroxy-4-hydroxymethylpyridyl - (5) - methyl] - p - chlorophenoxyethyl-disulfide. M.P. 145-146° C. (methanol).

Example 14

Analogously to the method set forth in Example 1, 5.4 g. 2-methyl - 3 - hydroxy - 4 - hydroxymethyl-5-mercaptop-methylpyridine are reacted with 8.78 g. benzoyl-methyl-thiosulfate to produce [2-methyl-3-hydroxy-4-hydroxymethyl - pyridyl - (5) - methyl]-benzoylmethyl-disulfide. M.P. 142° C. (190° C. decomposition)-(methanol).

Example 15

Analogously to the method described in Example 1, 3.6 g. 2-methyl-3-hydroxy-4-hydroxymethyl-5-mercaptop-methylpyridine are reacted with 9 g. p - bromobenzyl-thiosulfate to yield [2 - methyl - 3 - hydroxy-4-hydroxymethyl - pyridyl - (5)-methyl]-p-bromobenzyl - disulfide. M.P. 156-157° C. (methanol).

Example 16

Analogously to the method set forth in Example 1, 5.4 g. 2 - methyl - 3 - hydroxy - 4 - hydroxymethyl - 5 - mercaptomethylpyridine are reacted with 9.6 g. p-xylyl-thiosulfate to produce [2-methyl-3-hydroxy-4-hydroxymethyl-pyridyl-(5)-methyl]-p-xylyl-disulfide. M.P. 135-136° C. (methanol).

Example 17

Analogously to the method mentioned in Example 1, 5.4 g. 2 - methyl - 3 - hydroxy - 4 - hydroxymethyl - 5 - mercaptomethylpyridine are reacted with 8 g. β -naphthyl-methyl-thiosulfate to form [2 - methyl - 3 - hydroxy-4-hydroxymethyl - pyridyl - (5)-methyl]- β -naphthylmethyl-disulfide. M.P. 195-196° C. (methanol).

Example 18

Analogously to Example 1, the following compounds are obtained by reaction of 2 - methyl - 3 - hydroxy-4-hydroxymethyl-5-mercaptomethyl-pyridine with the corresponding thiosulfates:

Pyridoxolyl-methyl-disulfide
Pyridoxolyl-vinyl-disulfide
Pyridoxolyl-crotyl-disulfide
Pyridoxolyl-undecylenyl-disulfide
Pyridoxolyl-ethynyl-disulfide
Pyridoxolyl-propargyl-disulfide
Pyridoxolyl-naphthyl-disulfide
Pyridoxolyl-phenethyl-disulfide
Pyridoxolyl-4'-methoxybutyl-disulfide
Pyridoxolyl-4'-ethoxybutyl-disulfide
Pyridoxolyl-4'-butoxybutyl-disulfide
Pyridoxolyl-4'-benzyloxybutyl-disulfide
Pyridoxolyl-4'-propoxybutyl-disulfide
Pyridoxolyl-3'-benzoyloxypropyl-disulfide
Pyridoxolyl-4'-cinnamoyl-disulfide
Pyridoxolyl-3'-carboxypropyl-disulfide
Pyridoxolyl- β -methoxycarbonylethyl-disulfide
Pyridoxolyl-3'-toloxycarbonylpropyl-disulfide
Pyridoxolyl-2'-ethoxyheptylpropyl-disulfide
Pyridoxolyl-2'-carbamoylethyl-disulfide
Pyridoxolyl-4'-N,N-dimethylcarbamoylbutyl-disulfide

3,324,140

12

Pyridoxolyl - 3' - N,N - di - tert.butyl-carbamoylpropyl-disulfide
Pyridoxolyl - 2' - N - methyl - N - ethylcarbamoylethyl-disulfide
5 Pyridoxolyl-2'-morpholido-ethyl-disulfide
Pyridoxolyl-3'-piperididopropyl-disulfide
Pyridoxolyl-2'-hydroxyethyl-disulfide
Pyridoxolyl-2'-aminoethyl-disulfide
Pyridoxolyl-3'-diethylaminopropyl-disulfide
Pyridoxolyl - (3' - N,N - diethylamino-2'-methylpropyl)-disulfide
Pyridoxolyl-3'-piperidinopropyl-disulfide
Pyridoxolyl-chlorophenyl-disulfide
Pyridoxolyl-p-methoxyphenyl-disulfide
Pyridoxolyl-o-tolyl-disulfide
Pyridoxolyl-p-hydroxyphenyl-disulfide
Pyridoxolyl-o-aminophenyl-disulfide
Pyridoxolyl-2-amino-3-hydroxyphenyl-disulfide
20 Pyridoxolyl-2-methoxy-3-aminophenyl-disulfide
Pyridoxolyl-2-methyl-4-chlorophenyl-disulfide
Pyridoxolyl-2-methyl-3,6-dichlorophenyl-disulfide
Pyridoxolyl-2,3-dimethylphenyl-disulfide
Pyridoxolyl-piperidino-ethyl-disulfide
Pyridoxolyl-morpholino-butyl-disulfide
25 Pyridoxolyl-N-ethylpiperazino-ethyl-disulfide.

By repeating the preceding examples, using the required starting materials, all of the specifically and generically described compounds can be produced. The reaction conditions can, of course, be routinely varied by those skilled in the art to give more weight to certain variables of the process, such as reaction time, inhibition of side reactions, yield, and so on.

For a specific preferred embodiment of a pharmaceutical composition of this invention, the following is presented:

I. Tablets: Each tablet contains—
Mg.
Pyridoxolyl-allyl-disulfide ----- 100
Lactose ----- 200
Corn starch ----- 35
Magnesium stearate ----- 5
Talc ----- 20
II. Coated tablets: The core contains—
Pyridoxolyl-ether-disulfide ----- 150
Lactose ----- 100
Potato starch ----- 50
Gelatine ----- 4

The core is coated according to standard techniques with a mixture of sugar and arabic gum to make up a coated tablet with a total weight of 500 mg.

III. Syrup:
Pyridoxolyl-benzyl-disulfide ----- g 100
Sugar syrup ----- l 15
Saccharin ----- g 0.5
Para-hydroxy benzoic acid methyl ester ----- g 10
Para-hydroxy benzoic acid propyl ester ----- g 7
Aromatic stuffs

(The usual dosage is 15 ml.)

IV. Hard gelatine capsules: A mixture of—
Mg.
Pyridoxolyl - 2 - methyl - 3,6 - dichlorophenyl-disulfide ----- 120
Lactose ----- 50
Talc ----- 15
Vanillin ----- 1

is filled into hard gelatine capsules having 3 mm. in diameter.

70 From the foregoing description, one skilled in the art can easily ascertain the essential characteristics of this invention, and without departing from the spirit and scope thereof, can make various changes and modifications of the invention to adapt it to various usages and conditions. Consequently, such changes and modifica-

13

tions are properly, equitably, and intended to be, within the full range of equivalence of the following claims.

What is claimed is:

1. A member of the group consisting of a compound of the following formula and the acid addition salts thereof, 5

wherein:

R₁ and R₂ are each selected from the group consisting of hydrogen and acyl of an aliphatic hydrocarbon carboxylic acid of not more than 18 carbon atoms, and

R₃ is selected from the group consisting of (a) unsubstituted alkyl of not more than 20 carbon atoms; (b) alkyl of not more than 20 carbon atoms substituted by at least one member selected from the group consisting of halogen, hydroxyl, lower alkoxy, amino, mono-(lower alkyl)-amino, di-(lower alkyl)-amino, piperidino, morpholino, piperazino and piperazino substituted by lower alkyl, aralkoxy wherein the aryl portion is a hydrocarbon of 6 to 10 carbon atoms and the alkoxy portion is a lower alkoxy, acyloxy of a hydrocarbon monocarboxylic acid of not more than 9 carbon atoms, carbobenzoxy, carboxyl, esterified carboxyl of not more than 9 carbon atoms wherein the alcohol portion is a hydrocarbon alcohol of not more than 8 carbon atoms, unsubstituted —CONH₂, —CONH₂ substituted by lower alkyl, piperidino car-

10

bonyl, piperazino carbonyl, and morpholino carbonyl; (c) alkenyl of not more than 12 carbon atoms; (d) alkyne of not more than 3 carbon atoms; (e) x-carbocyclic aryl of up to 12 carbon atoms; (f) x-carbocyclic ar-lower alkyl of up to 12 carbon atoms in the carbocyclic portion; and x is selected from the group consisting of hydrogen and at least one of halogen, lower alkyl, lower alkoxy, hydroxy, nitro, amino, mono-(lower alkyl)amino, and di-(lower alkyl)amino.

2. A compound as defined in claim 1 wherein R₁ and R₂ designate hydrogen and R₃ is allyl.

3. A compound as defined in claim 1 wherein R₁ and R₂ designate hydrogen and R₃ is benzyl.

4. A compound selected from the group consisting of pyridoxolyl - ethyl - disulfide, pyridoxolyl - propyl - disulfide, pyridoxolyl-butyl-disulfide, pyridoxolyl-cetyl-disulfide, pyridoxolyl-lauryl-disulfide, and pyridoxolyl-allyl-disulfide.

5. A compound selected from the group consisting of pyridoxolyl-benzyl-disulfide, pyridoxolyl-p-xylyl-disulfide, pyridoxolyl - 2 - methyl - 3,6 - dichloro - phenyl - disulfide, and pyridoxolyl-2,3-dimethylphenyl-disulfide.
